(57) **CLAIM**

The ornamental design for a foldable chair with carrying straps, as shown and described.

DESCRIPTION

FIG. 1 is a perspective view showing our new design.

FIG. 2 is an alternative perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The darker broken lines shown on the fabric of the backrest, seat, and portion of straps represent stitching, other lighter broken lines shown in the drawing are for the purpose of illustrating environmental structure and form no part of the claimed design.

1 Claim, 8 Drawing Sheets
